HENRY DISSTON, OF PHILADELPHIA, PENNSYLVANIA.

Letters Patent No. 86,286, dated January 26, 1869.

IMPROVEMENT IN DEVICE FOR SIMULTANEOUSLY HARDENING AND STRAIGHTENING CIRCULAR-SAW BLADES.

The Schedule referred to in these Letters Patent and making part of the same.

To all whom it may concern:

Be it known that I, HENRY DISSTON, of Philadelphia, Pennsylvania, have invented a Mode of Simultaneously Hardening and Straightening Circular-Saw Blades; and I do hereby declare the following to be a full, clear, and exact description of the same.

My invention relates to an improvement in the mode of simultaneously hardening and straightening blades of steel, for which Letters Patent were granted to me on the 13th day of August, 1867; and

It consists in submitting circular-saw and other steel blades, while in a heated state, and while being submerged in the hardening-composition, to a pressure between rigid rods or bars, all of which is fully described hereafter.

In order to enable others skilled in the art to apply my invention, I will now proceed to describe the mode of carrying the same into effect, reference being had to the accompanying drawing, which forms a part of this specification, and in which—

Figure 1 is a front view, partly in section, of my apparatus for simultaneously hardening and straightening circular-saw and other steel blades;

Figures 2 and 3, transverse sections of the same on the line 1-2, fig. 1, showing the working-parts in different positions; and

Figure 4, a sectional plan view on the line 3-4, fig. 3. Similar letters refer to similar parts throughout the several views.

Within a metal trough or vessel, A, and secured to one side of the same, are three or any other suitable number of inclined guides or ways, B, grooved on their inner edges, and narrowed at the top of the trough, as plainly seen in figs. 2, 3, and 4.

Directly opposite these inclined ways, and secured to the other side of the trough, are straight upright bars, C C C, which support a metal frame-work, D, consisting of an edging, a a, of flat metal, to which is secured a number of vertical rods, b, placed at an equal distance apart from each other. (See fig. 1.)

A similar frame, D', is hinged to the lower edge of the frame D, in such a manner that it shall have a tendency to fall back from the latter, as indicated by the arrow in fig. 2.

Three wedge-shaped bars, E, each of which has a projection, e, adapted to the grooves of the inclined ways B, are arranged to slide between the latter and the hinged frame D', the bars being connected together at the top by a cross-piece, F', so that they may be simultaneously raised and lowered in the trough.

When these bars are elevated, the frame D' is permitted to fall back, as shown in fig. 2; but, by reason of their wedge-like shape and the inclined ways upon which they slide, the said bars force the hinged frame toward the frame D, when they are lowered into the trough, as shown in fig. 3.

A bent plate, d, which is secured to each side of the central bar F, projects between the rods b of the frames D and D', for a purpose described hereafter.

In using the apparatus, the trough A is filled, or nearly filled, with oil or other hardening-liquid, and the bars F are raised, as seen in figs. 1 and 2.

A circular-saw blade, X, while in a heated state, is then introduced between the fixed and hinged frames D and D', its lower edge resting upon the bent plates d, and its upper edge against the central bar F.

The wedge-shaped bars are then suddenly released from the suspension-chain, and permitted to fall, with the blade, into the trough, so as to submerge the saw-blade in the hardening-composition, the frames D and D' closing upon the blade simultaneously with its descent into the trough, so that, by the time the bars F have reached the limit of their downward movement, the blade is firmly gripped between the rods b of the two frames, and thus held until submitted, for a proper time, to the action of the hardening-composition.

In order to prevent the wedge-shaped bars from descending too far into the trough, the latter is provided at each end with stops h h, which are struck by rubber cushions i i, secured to the opposite ends of the cross-piece F', these cushions serving to reduce the shock caused by the sudden descent of the cross-piece upon the said stops.

In my former patent, of August 13, 1867, the saw-blades were strengthened, while submitted to the hardening-process, by being pressed between flat plates of metal; but, although this method answered well for narrow saw-blades and thin strips of steel, I have found in practice, that for circular-saw blades, or other plates having a large area, it is uncertain in its operation, inasmuch as the hardening-composition is prevented, by the pressure-plates, from coming in contact with the surface of the metal.

This objection, however, is entirely obviated by the use of the frames D and D', the rods b effectually straightening the blades, and preventing them from warping, and at the same time permitting the free passage of the hardening-liquid to their entire surfaces.

Upon elevating the bars F, the hardened plate is raised from the trough by the plate d, upon which it rests, the frame D' falling back, as before described, and permitting the withdrawal of the blade, and the introduction of a second, which is treated in the same manner.

I claim as my invention, and desire to secure by Letters Patent—

The mode, substantially as herein described, of simultaneously hardening and straightening circular-saw blades, by submitting them, while in a heated state, to a pressure between rigid bars or rods, while, at the same time, they are submerged in the hardening-composition.

In testimony whereof, I have signed my name to this specification, in the presence of two subscribing witnesses.

HENRY DISSTON.
